CLAIM

The ornamental design for a watercraft hull, as shown and described.

DESCRIPTION

FIG. 1 is a front elevation view of a watercraft hull according to an embodiment of our design;

FIG. 2 is a rear elevation view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is a perspective view taken from a bottom, front, left side of a watercraft hull according to another embodiment of our design;

FIG. 8 is a front elevation view thereof;

FIG. 9 is a rear elevation view thereof;

FIG. 10 is a right side elevation view thereof;

FIG. 11 is a left side elevation view thereof;

FIG. 12 is a top plan view thereof;

FIG. 13 is a bottom plan view thereof;

FIG. 14 is a perspective view taken from a bottom, front, left side of a watercraft hull according to another embodiment of our design;

FIG. 15 is a front elevation view thereof;

FIG. 16 is a rear elevation view thereof;

FIG. 17 is a right side elevation view thereof;

FIG. 18 is a left side elevation view thereof;

FIG. 19 is a top plan view thereof;

FIG. 20 is a bottom plan view thereof;

(Continued)

FIG. 21 is a perspective view taken from a bottom, front, left side of a watercraft hull according to another embodiment of our design;
 FIG. 22 is a front elevation view thereof;
 FIG. 23 is a rear elevation view thereof;
 FIG. 24 is a right side elevation view thereof;
 FIG. 25 is a left side elevation view thereof;
 FIG. 26 is a top plan view thereof; and,
 FIG. 27 is a bottom plan view thereof.

The broken lines in the drawings illustrate portions of the watercraft hull that form no part of the claimed design. The watercraft hull is shown with a symbolic break in its length. The breakaway symbols and any portions of the watercraft hull between the breakaway symbols do not form part of the claimed design.
